UNITED STATES PATENT OFFICE.

JESSE M. GARLINGTON, OF OTTAWA, ILLINOIS.

MATCH-BOX.

1,110,321.

Specification of Letters Patent. Patented Sept. 15, 1914.

Application filed December 29, 1913. Serial No. 809,176.

To all whom it may concern:

Be it known that I, JESSE M. GARLINGTON, a citizen of the United States, residing at Ottawa, in the county of La Salle and State 5 of Illinois, have invented certain new and useful Improvements in Match-Boxes, of which the following is a specification.

This invention relates to improvements in match boxes and in particular to a pocket 10 match box of generally rectangular form, constructed so as to be readily held and opened by the fingers of one hand, and having combined therewith a cigar cutter and cigar perforator.

15 One of the objects of my invention is to provide a simple and inexpensive article of this sort such as may be readily stamped and formed by automatic machinery.

Another object of my invention is to provide 20 a box that can be held in the palm of the operator's hand and the lid readily opened by movement of the thumb of the same hand.

A further object of my invention is to 25 provide a neat and attractive pocket match box having combined therewith a cigar cutter and a cigar perforator.

In the drawings Figure 1 is a perspective 30 view of my improved match box partially opened. Fig. 2 is a side elevation. Fig. 3 is an end elevation. Fig. 4 is a plan view of the base portion of my match box with the lid removed, parts being broken away. Fig. 35 5 is a fragmentary, vertical, sectional view taken on line 5-5 of Fig. 4, and Fig. 6 is a fragmentary, vertical, sectional view on the line 6-6 of Fig. 5.

In the drawings the numeral 1 indicates 40 in general the base or body portion of the box comprising the bottom part 2 with its upturned ends 3-3, and upturned sides 4-4.

The numeral 5 indicates in general the lid.

45 The base portion 1 of the box is of generally rectangular form, the depth being comparatively small, as compared with its length and width, so that the box may be well adapted for use as a vest pocket match 50 box. A portion of one of the sides 4 near one end is cut away as at 6, so as to facilitate the grasping and removing of a match. The corners of the base portion, where the sides 4-4 join the bottom 2 are pressed inwardly 55 to form elongated grooves 7 which are engaged by the inturned edges 8 of the down-

wardly extending lips 9 of the lid 5. The lips 9 extending downwardly from the longitudinal sides of the lid are bent to conform to the upturned sides 4 of the base portion; and the inturned lower edges 8 coacting with the grooves 7 securely holds the lid in slidable contact with the top of the sides 4 and ends 3 of the base section. One end of the lid 5 is provided with a downwardly extending lip 10, which when the box is closed, engages with the end 3 of the base section thereby insuring the sliding of the lid in but one direction. On the opposite end of the lid, a downwardly extending 65 ridge 11 is formed which, when the box is open coacts with the inner side of the ends 3 of the box thereby preventing the removal of the lid except by sufficient pressure to spring the lid up and away from the base 70 section, such pressure being necessary only in assembling the box.

To facilitate the opening and closing of the box by a finger and thumb movement of the same hand which holds it I have provided 80 a series of transverse corrugations 12 in the lid 5, and a similar series 13 in the bottom 2. The box being held right side up in the palm of an operator's hand it is evident that the thumb will naturally 85 engage the corrugations 12 of the lid and thus readily move the same to open or close the box.

A hole or perforation 14, is provided in the lid adjacent the end carrying the lug 10, 90 its edge being beveled downward, as at 15, to receive the tip of a cigar. The operation of forming the hole and its beveled edge is best performed by a punch having on its shank a conical shoulder, which after the 95 perforation of the metal by the punch end, comes in contact with the metal around the hole squeezing it to the desired form. The pressure thus applied to the metal around the hole hardens and toughens it, thus providing an efficient shank and durable cutting edge. The tip of a cigar being placed in the opening 14 and the lid closed, it is evident that the pressure of the end of the base portion 3 against the tip will cause the sharp edge of the hole 14 to sever it from the body of the cigar, making a neat, clean cut.

I have also provided in the base portion 110 of my box near one side a cigar perforator which comprises a flat strip 16, one end of which is formed into a round pin 17 extend-

ing through an opening 18 in the end wall 3 adjacent the bottom 2. A finger button 19 has a shank 20 extending upward through a slot 21 in the bottom of the box. The shank 20 is riveted over to engage the flat strip 16 so that as the button is moved from one end to the other of the slot the strip 16, together with the perforating pin 17, is correspondingly moved. Movement of the button 19 toward the end of the box near which it is attached projects the pin 17 through the opening 18 performing the cigar perforating act. The end of the strip 16 away from the pin 17 is curved or humped upward as at 22 to insure frictional engagement of the strip with the bottom of the box, thus preventing its accidental displacement. The perforating pin is positioned at the bottom of the base section near one side 20 so that if the operator wishes to make an axial opening in the cigar, the partially open lid forms with one of its downwardly extending sides a stop or abutment against which to hold the cigar in making the perforation to insure its coaxial relation with 25

the pin. Obviously a transverse perforation may be made when the lid is closed.

Whereas I have illustrated and described a single embodiment of my invention it is evident that various changes may be made 30 without departing from the spirit or scope thereof.

Having described my invention, what I claim is:—

The combination with a box having a tray 35 shaped base section and a lid, of grooves formed in the base section at the juncture of the sides with the bottom, and downwardly extending lips on the lid engaging with the said grooves, for sliding engagement therewith, one of the side walls near its end being cut away substantially to the bottom of the base section to provide a finger recess.

In testimony whereof I hereunto set my 45 hand in the presence of two witnesses.

JESSE M. GARLINGTON.

In the presence of—

MAUDE HITE,
RICHARD J. DUNN.
